CIRCUIT BREAKER

Herbert J. Crabbs and Herbert L. Rawlins, Wilkinsburg, Pa., assignors to Westinghouse Electric & Manufacturing Company, East Pittsburgh, Pa., a corporation of Pennsylvania

Application August 15, 1934, Serial No. 739,892

10 Claims. (Cl. 200—117)

Our invention relates to circuit interrupters and is particularly concerned with the improvement of expulsion circuit breakers, which utilize a gas blast for extinguishing the arc which is drawn 5 incident to the circuit interrupting operation.

These devices take a multitude of forms, but perhaps the best known, and certainly the most widely used, is the so-called expulsion fuse. Expulsion fuses fulfill a very definite mission in the 10 electric art, in that they constitute a means whereby protection, against abnormal circuit conditions, may be given to electrical apparatus at a very low cost. Their application is limited only because of the fact that they are inherently one 15 operation device, and must be serviced after each operation.

During the circuit interrupting operation, the heat of the arc which is established by the melting of the fusible link causes the evolution of large 20 quantities of gas from the walls of the main fuse tube, and this gas, in venting, flows expulsively through the arc, thereby effecting its extinguishment. The device is restored to an operative condition following each operation by replacing 25 the used fusible unit with a new one.

One of the most successful commercial forms 30 of expulsion fuse devices comprises a tube, of fiber or other material which is capable of evolving arc extinguishing gas when placed in proximity to an electric arc, conducting terminal members mounted at the ends of the tube, and a replaceable fusible unit disposed within the tube 35 for connecting the terminals and for opening the electrical circuit therethrough upon the occurrence of predetermined overload conditions. One end of the tube is normally closed and the other end is normally open. Upon the occurrence of an overload or other abnormal condition 40 the fusible element melts and an arc is established within the fuse tube.

In the ordinary operation of these devices, they 45 are called upon to interrupt overloads of widely varying magnitude, and, since the dimensions of the main tube must be sufficiently large to accommodate the largest magnitude arc which may be established therein, some difficulty has been experienced with the prior art devices in the interruption of low-current overloads. This difficulty has arisen because of the fact that the arcs 50 which are produced by low-magnitude overloads are of comparatively small cross sectional area, and thus do not contact the gas evolving walls of the main tube sufficiently intimately to produce an adequate amount of arc extinguishing 55 gas.

The difficulty of satisfactorily interrupting low-current magnitude arcs is further aggravated, where a simple link-type fusible unit is used because of the fact that only a small portion of the fusible element is melted by the overload, 5 and, since little gas is evolved, the remaining conducting portions of the fusible means are not expelled from the tube so as to draw a long arc. The result is that on low current overloads only 10 a short arc is drawn and little gas is produced for effecting its extinguishment.

To overcome these difficulties, spring biased 15 fusible units have been developed, and it is with the improving of these devices that the present invention is especially concerned.

Spring biased fusible units are much more satisfactory than the older devices. Upon the occurrence of large magnitude overloads, the operation is substantially the same as for the unbiased units. The heavy-magnitude overloads cause a 20 substantially instantaneous fusion of the fusible element with a resultant large evolution of gas in the walls of the fuse tube and the combined result is to expel the entire fuse means from the tube, thereby securing a long arc which is quickly 25 extinguished by the out-flowing blast of gas. When the device is interrupting low-magnitude overloads, the action of the biasing springs is such as to secure a long arc immediately following the fusion of the fusible element, and the devices 30 are so proportioned that this arc is too long to be self-sustained whether or not the gas evolution is very large.

As a further improvement for very low-current 35 operation, an auxiliary tube of insulating material having a cross-sectional area considerably less than that of the main tube is disposed about the fusible element proper. The walls of this tube are relatively weak and are practically immediately ruptured when a large-current-magnitude 40 is drawn, but are capable of aiding very considerably in the extinction of small-magnitude arcs by the provision of a suitably directed stream of arc extinguishing gas.

Certain difficulties have arisen in the utilization 45 of spring biased fusible elements. Most of these devices have utilized a single tension spring which is stressed when the renewable fuse unit is installed within the main tube of the interrupter. Due to difference in the dimensions of the tubes 50 and in the manner of servicing the devices, the amount of stress on the spring is a variable quantity and the calibration of the fusible element is thus rendered more or less uncertain. It would appear that the solution of this problem lies in 55

the provision of a spring biased fusible element which utilizes a compression spring which is normally stressed at all times. Through this arrangement, absolute accuracy of calibration may be assured, since the fusible element may be entirely assembled at the factory, the spring being placed under a definite predetermined stress at that time.

Another difficulty exists in the design of a commercially satisfactory fuse device particularly when it is intended that that device should be used as refill units for fuse structures now in existence. Different electrical manufacturers have utilized different sized terminals, tubes, and the like for their expulsion fuses. Practically all existing power systems utilize a number of different fuse structures, and to simplify the problem of maintenance and to reduce the cost of the stocks of replacement fuses which must be carried, it is highly desirable that the refill fuse unit be provided with suitable means for allowing the device to be utilized in any of the existing structures.

The principal object of our invention, therefore, is to provide an improved, universally applicable replacement fuse structure which shall be suitable for use in all existing types of expulsion fuse devices, and which shall be superior in its operating characteristics to the previously known devices.

Another object of our invention is to provide an improved fuse unit for expulsion fuses or similar devices which shall be provided with two serially connected fusible sections, one of which is adapted to fuse substantially instantaneously upon the occurrence of high current overloads and the other of which is adapted to fuse following the currents of prolonged low-magnitude overloads.

A further object of our invention is to provide a spring biased fusible element wherein the biasing force exerted by the spring on the fusible section is accurately adjusted to a fixed value during the manufacture of the fuse, in order to secure the maximum possible accuracy of calibration of the device.

A second further object of our invention is to provide a spring biased fusible element which shall utilize a compression spring for supplying a tensioning force to the fusible section of the element.

A still further object of our invention is to provide an improved terminal means for use with electric fuses generally, our improved means to permit a single fuse refill unit to be used with structures having fuse engaging means of differing dimensions, our improved terminal means to utilize no loose parts which might become lost and to be so arranged that a good electrical connection is assured at all times.

These and other objects of our invention will be made more apparent from the following description of a preferred embodiment of our invention. Referring to the drawing:

Figure 1 is a sectional view, partially in elevation, of an expulsion fuse utilizing a refill unit which includes the principal features of our invention.

Figure 2 is an enlarged sectional view, partially in elevation, of the refill unit forming a part of the fuse structure shown in Fig. 1.

Figure 3 is a fragmentary elevation view showing the fusible sections of the refill unit illustrated in Fig. 2.

Figure 4 is a developed plan view of the upper

terminal of the refill unit shown in the other figures of the drawing.

Figure 5 is an enlarged sectional view on the line V—V of Fig. 2.

Figure 6 is a fragmentary perspective view of the upper terminal portion of the refill element shown in Figs. 1 and 2, and

Figure 7 is a developed plan view of a modified upper terminal member suitable for use with the refill unit illustrated in the other figures of the drawing.

The expulsion fuse structure which is shown in Fig. 1 includes a main tube 1 of fiber or other suitable insulating material, which is threaded at its upper end and which is provided with a metallic ferrule 3 adjacent its lower end. A suitable hollow contact member 5 is threaded onto the upper end of the main tube 1, and the control opening in this member is adapted to be closed by a suitable cap member 7 which also serves the function of holding the upper button-type terminal 11 of the refill unit 9 in contact with the upper contact member 5. The refill unit itself is positioned within the main fuse tube 1, and is provided with a flexible conductor 13 for engaging the screw connection 15 which forms a part of the lower ferrule 3 in order to complete the electrical circuit through the device. The lower end of the fuse tube 1 is normally open in order to allow a free out-flow of the gas which is evolved from the walls 20 of the main tube during the circuit interrupting operation.

In order to obtain the greatest possible extension of the operating range of the fuse, the refill unit is provided with two serially connected fusible elements, each of which will be described in some detail later. One of these elements is adapted to fuse substantially instantaneously upon the occurrence of heavy overloads or other similar circuit disturbances, and the other element is adapted to fuse after a time delay upon the occurrence of prolonged moderate overloads. This arrangement, while giving adequate protection to the connected equipment, serves to minimize undesirable and annoying discontinuities in the flow of power through the system.

The upper terminal portion 11 of the refill element 9, as is shown particularly in Figs. 2 and 4, comprises a flat sheet of conducting material which is cut so as to form a plurality of cooperating circular sections 17, 18, 19 and 21, which may be bent one over the other so as to define button or cap-type terminals of at least two different dimensions. The method of bending this terminal portion 11 is shown particularly in Fig. 6, wherein the several elements have been bent to form the largest possible button or cap-type terminal for the refill element. If a cap portion having a smaller diameter is desired, the larger of the cooperating sections 17 of the upper terminal member 11 is bent back and forth a few times so as to cause it to be broken away from the remaining sections, thus leaving a cap having the diameter of the section 19. If it is desired to use the device in a fuse structure which is provided with a screw terminal at its upper end, all of the circular sections are broken from the remaining shank portion 23 of the upper terminal, and the semi-circular cutout portion 25 is utilized for engaging the terminal screw. The device illustrated is thus provided with means for accommodating it to at least three different forms of fuses, and it is of course a simple matter to provide additional sections on the terminal member if the

device must be capable of accommodating itself to other structures.

By forming the entire terminal portion 11 from a single sheet of conducting material, all 5 loose parts are eliminated, and one serious objection to some of the prior art devices is overcome. Also, this arrangement assures a good electrical connection between the refill terminal and the refill itself, thus preventing high resistance contacts and their accompanying dangers.

The lower end of the shank portion 23 of the upper terminal member 11 is somewhat narrower than the main body of that portion and is adapted to extend into suitable slots 29 provided in the upper end of an auxiliary fuse tube 27 which forms a part of the refill unit. The lower edges 31 of the body portion 23 serve as shoulders for engaging the ends of the slots 29.

20 Two holes 33 are punched in the reduced section of the body portion 23 for allowing the passage of two rivets 35 which are adapted to electrically and mechanically connect the upper terminal 39 of the instantaneous fusible element 37 thereto. This fusible element 37 comprises a flat strip of conducting material which, in addition to the enlarged terminal portion 39 for engaging the lower end of the upper terminal member, is provided with a portion 41 of reduced 25 cross-sectional area, which is adapted to fuse substantially instantaneously upon the passage therethrough of predetermined magnitude currents, and a lower portion 43 which is adapted to be soldered by a low melting point solder to a flat conducting member 45 of substantially the same cross sectional dimensions as the lower portion of the fusible element itself.

20 The member 45 is formed of a resistance material such as German silver or the like, and is soldered at its lower end, likewise by a low melting point solder, to a terminal strip 47, the lower end of which, in turn, is soldered by a high melting point solder to the upper end of the flexible conductor 13. The member 45 and the two associated soldered joints comprise the second fusible element.

The auxiliary fuse tube 27 is of sufficient length to enclose the fusible portion 41 of the upper fusible element 37 and the two soldered 50 connections of the member 45 positioned beneath that element. At its lower end, the auxiliary fuse tube 27 is provided with a hollow cylindrical member 49, which may be of metal, for positioning the upper end of the compression spring 51, the upper end of this spring being adapted to abut against the lower end of the auxiliary fuse tube 27 when the device is in the normal operative position. The lower end of the compression spring 51 engages a suitable funnel shaped member 53 which is rigidly soldered to the flexible conductor, in the position shown in Fig. 2, during the assembling of the device.

As mentioned previously, the shoulders 31 which form a part of the upper terminal member 11 engage the lower ends of the slots 29 cut in the auxiliary fuse tube 27, and serve to transmit the reaction force of the compression spring 51 to the upper end of the upper fusible portion 41 of the refill element. The biasing force of the spring is transmitted to the lower end of the lower fusible portion of the refill unit due to the fixed engagement of the funnel shaped member 53 with the flexible conductor. Through this arrangement, it is possible to utilize a single compression spring, which may be stressed dur-

ing the manufacture of the refill unit to any desired value, for producing a tensioning force upon both of the fusible elements of the refill unit.

The resistance of the member 45 is so proportioned that the heating produced by the prolonged flow therethrough of a predetermined current is capable of effecting the melting of the low melting point solder which serves to connect that member with the upper fusible element 37 10 and the terminal portion 47. When this occurs the biasing action of the spring 51 effects the opening of the electrical circuit through the refill unit at that point. The accurate tensioning of the fusible elements which is made possible by 15 the utilization of a compression spring which is adjusted at the factory, assures accurate calibration and accurate maintaining of the calibration of both of the fusible elements.

Upon the occurrence of a very heavy overload 20 in the controlled circuit, the upper fusible element is melted at the portion 41, substantially instantaneously, and the compression spring 51 is then free to move all of the conducting portions of the refill unit disposed beneath the upper fusible portion 25 out of the auxiliary fuse tube 27. The arc drawing operation, following the occurrence of very heavy overload takes place, however, at extremely high speed, and simultaneously with the separation of the terminal portions 39 and 43 30 of the upper fusible element, which is effected by the biasing spring 51, there is a large evolution of the gas from the auxiliary fuse tube 27 which may effect a rupture of the tube accompanied by an expanding of the arc into the main fuse tube 1. 35

If the arc energy is very large, the rate of gas evolution soon becomes sufficient to effect a very rapid expelling of the auxiliary fuse tube 29, the spring 51, and the flexible conducting member 13 from the lower open end of the main tube 1, with 40 the result that a long arc is established therewithin. This arc contacts the walls of the tube and evolves a very considerable quantity of arc extinguishing gas which gas in venting flows expulsively through the open lower end of the fuse 45 tube, thereby effecting the extinguishment of the arc.

Upon the occurrence of a low magnitude overload, the resistance member 45 begins to heat, and if the overload persists for a sufficient period 50 of time the heating causes the low melting point solder to be melted. Simultaneously with the melting of this solder the compression spring 51 moves the flexible lead 13 and the terminal strip 47 affixed thereto in the direction of the lower, 55 open end of the main fuse tube 1, and effects the establishing of an arc having at least a portion thereof within the auxiliary tube 27.

The release of the compression spring 51 by the fusing of either fusible element usually produces 60 sufficient reaction forces to cause the spring, the flexible lead 13, and the terminal 47 affixed thereto to be moved entirely out of the main fuse tube 1. Even if this is not done, however, there is a sufficient separation of the current-carrying 65 parts to assure a rapid extinction of low magnitude arcs.

The cross-sectional dimensions of the fusible elements are such that they may be moved into the central opening within the spring 51 when 70 the spring expands during the operation of the device. This assures that there will be no jamming or failure of the device to operate. The presence of the auxiliary fuse tube during the interruption of low magnitude overloads is of par- 75

ticular value in assuring that the arc shall be subjected to an adequate blast of arc extinguishing gas.

The modified upper terminal member 111 which is illustrated in Fig. 7 is essentially similar to the previously described member 11. Similar to that member, it comprises a flat sheet of conducting material which is cut so as to define a plurality of cooperating circular sections 117, 118, 119, 120 and 121, which may be bent one over the other so as to define a button or cap-type terminal of at least two different dimensions. The chief differences between the two members reside in the provision of two shank portions 123 in the modified structure and in the arrangement of the circular sections.

From the foregoing it will be seen that we have provided an improved refill unit for use with expulsion fuses or similar devices which possess numerous advantages over the devices previously known to the art. Our improved refill unit is provided with a novel terminal means for permitting it to be used with devices whose physical dimensions vary over a considerable range. Moreover, it includes two serially connected fusible elements each of which is capable of fusing upon the occurrence of differing predetermined conditions, and a single compression spring for submitting those elements to a substantially constant tensioning force at all times. Further, we have shown how the features of our improved refill unit may be embodied into a device which utilizes an auxiliary fuse tube for aiding in the extinction of low magnitude overloads.

While in accordance with the patent statutes, we have disclosed the foregoing details of a preferred embodiment of our invention, it is to be understood that many of these details are merely illustrative, and that variations in their precise form may be possible and necessary in many applications. It is our desire, therefore, that the language of the accompanying claims shall be accorded the broadest reasonable construction, and that our invention shall be limited only by what is expressly stated therein and by the prior art.

We claim the following as our invention:

1. A replacement fuse means, comprising a fusible element, terminal means for said element, and a compression spring, which is stressed during the manufacture of said means, for subjecting said fusible element to a substantially constant tension stress at all times, one of said terminal means comprising a flat sheet of metal which is cut so as to provide a plurality of cooperating sections which may be bent so as to form button terminals of at least two different sizes.

2. A replacement fuse unit comprising a fusible element, terminal means electrically and mechanically connected to either end of said element, one of said terminal members comprising a flat sheet of conducting material which is cut so as to form a body portion having shoulder members formed integral therewith and a plurality of cooperating sections which may be bent so as to form button terminals of at least two different sizes, an auxiliary fuse tube disposed so as to enclose said fusible element, and a normally stressed compression spring for subjecting said fusible element to a substantially constant tension stress at all times, one end of said stressed spring being

mechanically connected to the other of said terminal members, and the other end of said spring abutting against one end of said tube, the other end of said tube engaging said shoulder portions in order to transmit the reaction force of said spring to said first mentioned terminal member. 5

3. A terminal means for a fusible element comprising a flat sheet of metal which is cut so as to form a plurality of cooperating sections which may be bent so as to form terminals of at least 10 two different dimensions.

4. A terminal member for an electric fuse comprising a flat sheet of conducting material having cuts therein forming a plurality of cooperating circular sections which may be selectively bent so as to form circular terminal members of at least 15 two different diameters.

5. A terminal member for an electric fuse comprising a flat sheet of conducting material having a shank portion and a plurality of cooperating 20 sections which may be bent so as to form button terminals of at least two different dimensions, the axis of said shank portion being substantially perpendicular to the plane of said button terminal means. 25

6. A terminal member for an electric fuse comprising a flat sheet of conducting material having a body portion of less width than length and a plurality of cooperating circular sections which may be selectively bent so as to form circular, 30 button type terminals of at least two different diameters, the longitudinal axis of said body portion being substantially perpendicular to the plane of said button terminal means. 35

7. A terminal means for a fusible element comprising a plurality of integrally formed, cooperating portions which define a button head of predetermined transverse dimensions, and means whereby at least one of said portions may be readily broken away to effect a change in the 40 transverse dimensions of said button head.

8. A terminal means for an electric fuse comprising a shank, a plurality of integrally formed, cooperating portions which define a button head 45 of predetermined transverse dimensions at one end of said shank, and means whereby at least one of said cooperating portions may be readily broken away to effect a reduction in the transverse dimensions of said button head.

9. A terminal member for an electric fuse comprising a flat sheet of metal, cut so as to form a plurality of integral cooperating sections which may be bent to form a button head of predetermined transverse dimensions, and means whereby at least one of said sections may be readily 55 broken away from said sheet to effect a change in the transverse dimensions of said button head. 65

10. A terminal member for an electric fuse comprising a flat sheet of metal, cut so as to define a plurality of integral portions which co- 60 operate to form a shank and a button head of predetermined transverse dimensions affixed to said shank, the longitudinal axis of said shank being substantially perpendicular to the plane of said button head, and means whereby at least one of 65 said portions may be broken away from said sheet to reduce the transverse dimensions of said button head.
